Primary Examiner — Cynthia Ramirez(74) *Attorney, Agent, or Firm* — Flynn, Thiel, Boutell & Tanis, P.C.(57) **CLAIM**

The ornamental design for a stand for a monitor, as shown and described.

DESCRIPTION

FIG. 1 is a top front perspective view of a stand for a monitor showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a right side view thereof when the present stand is combined with a monitor.

The broken line showing of a monitor is included for the purpose of illustrating environment and forms no part of the claimed design.
